BOILER

Ernst Tuckermann, Esbo, Finland, assignor to
 H. W. Guettler, President of Fibre Making
 Processes Inc., Chicago, Ill.

Application February 14, 1933, Serial No. 656,673,
 and in Finland January 29, 1932

4 Claims. (Cl. 122—39)

This invention relates to boilers, and has to do with boilers of the water tube type.

One of the main objects of the invention is to provide a boiler of high efficiency, which steams quickly and is capable of developing exceptionally high output to meet sudden demands. More specifically, an object of my invention is to provide a boiler comprising water tubes which are inclined upward at a sharp angle and enclose the combustion space of the furnace so as to be exposed directly to the radiant heat from the fire as well as to the hot products of combustion. A further object is to provide means for injecting water into the respective tubes, at the lower portion thereof, and for atomizing the injected water so that the resultant small particles of water are quickly converted into steam by heat derived from the tubes. Further objects and advantages of my invention will appear from the detail description.

20 In the drawings:—

Figure 1 is a semi-diagrammatic transverse vertical sectional view through a boiler embodying my invention, parts being broken away and parts being shown in elevation;

25 Figure 2 is a view similar to Figure 1, but illustrating a modified form of the invention; and

Figure 3 is a vertical sectional view through one of the water tubes and associated parts of the boiler shown in Figure 2, on an enlarged scale, parts being shown in elevation.

The boiler illustrated in Figure 1 comprises two upper drums F, lower drum C below and mid-way between and in direct communication with drums F, inclined tubes B opening at their upper ends into the lower portions of the respective drums F, and atomizing injectors D mounted in the lower ends of tubes B.

35 The tubes B are disposed at opposite sides of a suitable grate R and extend upward and inward over the grate, these tubes and the drum C substantially enclosing combustion space E of the furnace, suitable refractory being disposed between tubes B and drum C as shown.

A pump P of known type, conveniently driven 40 by an electric motor M, has its intake connected to the lower portion of drum C, and its discharge connected to the lower end of the respective injectors D. Water is supplied to drum C from a pre-heater, in a known manner, the normal water 45 level in this drum being that shown. The water delivered under pressure to the respective injectors D is discharged from the latter into tube B through a plurality of openings in the injectors, as indicated by the arrows. Conveniently, these 50 openings may be arranged to impart a whirling

motion to the water within the tube B, and baffle members b are preferably provided between the tube and the injector, these members being arranged to assure an approximately spiral path of travel of the water within tube B, as indicated. 60 This assures that the water is brought into intimate contact with the tube wall so as to absorb heat from the latter with great rapidity, which contributes to maximum heat transfer. Since the tubes B extend inward over the combustion 65 space E, and are directly exposed to the radiant heat of the fire as well as to the hot products of combustion, extremely rapid steaming and high efficiency are obtained.

The steam generated within tubes B flows 70 into drums F, from which it may be withdrawn as required. If desired, the steam withdrawn from drums F may be passed through a super-heater of known type (not shown) in a known manner, as will be readily understood by those familiar with 75 this art.

In the modified form of Figure 2, I provide a moving grate R', and tubes B open into the lower portion of a single steam drum F which communicates with the top of drum C through a valve G, which valve is normally closed. Water is supplied to drum C in a known manner, preferably from a pre-heater of known type, the normal water level in this drum being that shown. Drum C is exposed to the combustion space so that the 80 water within this drum is heated by the radiant heat from the fire, and by the hot products of combustion, to proper temperature for generating 85 steam.

A fitting A is provided at the upper end of each 90 of the tubes B and contains a flap valve a (Figure 3) effective for closing the upper end of the tube and preventing back pressure therein due to accumulation of steam within drum F. This valve normally occupies the dotted line position of 95 Figure 3.

In Figure 2 I have shown two different forms 100 of injectors, either of which may be used, as desired. A fitting I is suitably secured to the lower end of the righthand tube B of this figure and is provided, adjacent its lower end, with a nipple N (Figure 3) which communicates with the fitting through an opening controlled by a flap valve K normally held in open position shown in dotted lines, in any suitable manner. Nipple N is connected by a valve controlled pipe L to the lower portion of drum C. A dished ring member S is slidably mounted on the lower end of injector nozzle D, which is slotted as shown, and closes the 110 space between the nozzle and the surrounding

wall of the fitting. Member S may be adjusted by means of a rod r suitably attached thereto and passing through a suitable stuffing box in the lower end of the fitting. In its full line position of 5 Figure 3, member S is above the opening from nipple N into the fitting, and in its dotted line position it is below this opening, as clearly shown in Figure 3. The steam space of drum C is connected by a valve controlled pipe H to an enlargement i of fitting I, which enlargement is disposed above and adjacent the uppermost position of member S, and opens into a Venturi element V of the fitting. Since steam is continuously drawn from drum F, in the use of the boiler, the pressure 10 in drum C is normally higher than that in drum F. By properly adjusting the valves in pipes H and L, the rate of flow of water and steam from drum C to fitting I can be regulated as required, and the desired difference in pressure between 15 drums F and C can be maintained. The disposition of drum C relative to drum F and the combustion space E, contributes to maintaining the desired higher pressure within drum C.

With member S in its uppermost position, water 20 is admitted from drum C into the lower portion of injector nozzle D. This water is withdrawn from the nozzle and is effectively broken up and atomized, by the steam flowing at high velocity through the venturi and about the nozzle, and the 25 mixture of steam and water has a whirling motion imparted thereto in the manner previously described. In this manner the water is separated into small particles which are forced into intimate contact with the hot tube wall so as to be quickly 30 converted into steam with a flash action. This prevents objectionable dryness of the tube B while assuring maximum heat absorption with resulting rapid generation of steam.

By regulating the flow of steam and water to 35 the fitting I, the rate of generation of steam can be varied within wide limits. If desired, the flow of steam from drum C to selected tubes B can be cut off thus materially reducing the generation of steam, in which case these tubes will be maintained filled with water from drum C so as to 40 avoid any danger of burning out of such tubes. In Figure 2 I have shown one pipe H connecting the steam space of drum C to enlargement i of fitting I, and in Figure 3 I have shown two such pipes. 45 It will be understood that the connections from drum C to the fitting I may be varied as required, and that suitable valves are provided, as shown, for regulating the flow of the steam and the water as conditions may require.

50 Referring now to the tube B at the left side of Figure 2, a fitting O of bulbous shape is suitably secured to the lower end of this tube. An injector nozzle D' extends upward through fitting O and through a venturi V in the lower end of the tube. 55 This nozzle D' is open at its upper end and is connected, at its lower end, to the lower portion of drum C by pipe L. Fitting O is connected by pipe H to the steam space of drum C, and the opening of nozzle D' is preferably so formed as to 60 impart whirling motion to the water discharged 65

therefrom. The steam flows at high velocity from the venturi and about the nozzle, and acts to withdraw the water from the nozzle and to atomize it so that the small particles of water are quickly converted into steam by contact with the hot tube 80 wall.

I claim:

1. In combination in a boiler, an upper drum structure, tubes communicating at their upper end with said structure and extending downward therefrom at opposite sides thereof, a steam and water drum extending between the tubes at the upper portions thereof and below said drum structure, said drum and said tubes defining a combustion space, injector nozzles extending into 90 the lower ends of the tubes, and means for delivering water under pressure from said steam and water drum to said nozzles. 95

2. In combination in a boiler, an upper drum structure, tubes communicating at their upper ends with said structure and extending downward therefrom at opposite sides thereof, a steam and water drum extending between the tubes at the upper portions thereof and below said drum structure, said drum and said tubes defining a 100 combustion space, injector nozzles extending into the lower ends of the tubes, and a pump having its intake connected to the water space of the steam and water drum and its discharge connected to said nozzles. 105

3. In combination in a boiler, an upper drum structure, tubes communicating at their upper ends with said structure and extending downward therefrom at opposite sides thereof, a steam and water drum extending between the tubes at the upper portions thereof and below said drum structure, said drum being out of direct communication with said upper drum structure and defining with the tubes a combustion space, fittings at the lower ends of the tubes, injector nozzles 110 extending from the fittings into the lower ends of said tubes, connections between said nozzles and the water space of said steam and water drum, and means for admitting steam from the steam and water drum into the tubes and about 115 the nozzles. 120

4. In combination in a boiler, an upper drum structure, tubes communicating at their upper ends with said structure and extending downward therefrom at opposite sides thereof, a steam and water drum extending between the tubes at the upper portions thereof and below said drum structure, said drum being out of direct communication with said upper drum structure and defining with the tubes a combustion space, fittings 130 at the lower ends of the tubes, said fittings being provided with venturis, injector nozzles extending from the fittings and through the venturis into said tubes, water connections between said nozzles and the water space of the steam and water drum, and steam connections between the steam space of said steam and water drum and the respective fittings below said venturis. 135

ERNST TUCKERMANN. 140
